DESULFURIZING MINERAL OIL USING AN UNSATURATED NITRILE WITH OR WITHOUT CAUSTIC

Abraham Schneider, Philadelphia, and James L. Jezi, Swarthmore, Pa., assignors to Sun Oil Company, Philadelphia, Pa., a corporation of New Jersey

Application April 26, 1954, Serial No. 425,478

9 Claims. (Cl. 196—24)

This invention relates to the refining of mineral oil, and more particularly to the reduction of the objectionable mercaptan content of mineral oil fractions.

The mercaptan content of various mineral oil fractions presents a difficult problem, particularly with regard to odor. Various means have been proposed previously for overcoming this problem, but none have been entirely satisfactory. Ordinary caustic treatment of mineral oil fractions produces some reduction of objectionable mercaptan content, but the reduction is in many cases insufficient to produce a satisfactory product.

According to the present invention, a mineral oil treating process is provided which produces a highly satisfactory reduction in objectionable mercaptan content. The treatment according to the invention is capable of providing a greater reduction in objectionable mercaptan content than prior art treatments, e. g. with caustic soda.

In the process of the present invention, mineral oil is contacted with a treating compound having the formula:

where R, R', and R'' are each selected from the group consisting of hydrogen, methyl, and ethyl radicals. Examples of suitable such compounds are acrylonitrile, which is a preferred compound for use according to the invention, alpha-methyl acrylonitrile, betaethyl acrylonitrile, betadimethyl acrylonitrile, alphamethyl-betadimethyl acrylonitrile, etc. The amount of treating compound used is generally small, e. g. in the range from 0.001 to 5 weight percent of the petroleum material treated, more preferably from 0.01 to 1 weight percent. In the event that any excess of treating compound is used, the excess can if desired be removed from the petroleum material, e. g. by scrubbing the petroleum material with water or an alkaline solution, or by distillation of the treating compound from the petroleum material if the treating compound is more volatile than all or part of the petroleum material.

The treatment according to the invention can be performed in the presence or absence of an alkaline material such as ammonium, alkali metal, or alkaline earth metal oxide, hydroxide or carbonate. The treatment may be at room temperature or at higher temperatures, e. g. up to 600° F. Preferably, if the temperature is below 200° F. the treatment is performed in the presence of such oxide, hydroxide or carbonate. Preferred temperatures, when no alkaline material is employed, are 200° F. to 600° F., more preferably 300° F. to 500° F.

The treatment according to the invention is believed to involve chemical reaction of the treating compound, e. g. acrylonitrile, with objectionable constituents of the petroleum material, e. g. mercaptans. The reaction product may, if desired be left in the oil, or if desired it may be removed by suitable means, such as washing with water, treatment with adsorbent material such as clay, etc. In the case where an alkaline material such as caustic soda is contacted with the petroleum material, a part of the reaction product may be removed with the alkaline material upon separation of the latter from the petroleum

2

material. Hydrolysis of cyano groups in the reaction product to carboxyl groups may take place, and the carboxyl-containing hydrolysis product may be removed in the form of a salt with the alkaline material. Such hydrolysis product can be precipitated from the alkaline material by treatment with lime.

The treatment according to the invention is effective to overcome the objectionable effects, not only of mercaptans in petroleum materials, but also of other non-hydrocarbon constituents of petroleum, e. g. hydrogen sulfide. The treatment of the invention may advantageously be applied to various petroleum materials such as natural gas, refinery gases, dry gases, liquefied petroleum gases, gasoline, kerosene, spirits, gas oil, furnace oil, diesel fuel, jet fuel, lubricating oil, crude oil, etc.

The invention will be further described with reference to the attached drawing, wherein Figure 1 illustrates treatment of gasoline with fresh caustic soda in the presence of acrylonitrile, Figure 2 illustrates similar treatment with spent caustic soda, and Figure 3 illustrates regeneration of spent caustic soda by contact with acrylonitrile.

In the process of Figure 1, gasoline to which acrylonitrile has been added to form, for example, a 0.1 percent solution is contacted with agitation with caustic soda, e. g. five volumes of caustic per 100 of gasoline. The contacting can be conducted for example at ordinary temperature without heating. At the end of the contacting step, the mixture is allowed to settle, and the layers are separated. The refined gasoline layer will be found to have been greatly improved in properties such as mercaptan and H₂S content, etc., the improvement being substantially greater than that obtainable by similar caustic treatment in the absence of acrylonitrile.

The gasoline treated as described above may have been given a preliminary treatment in the absence of treating compound according to the invention. For example, it may have been treated with caustic soda, etc.

The process of Figure 1 illustrates improvement in caustic treating by use of acrylonitrile. Acrylonitrile and other treating compounds according to the invention can also be used to advantage in other refining operations; for example they can be added to various petroleum refinery streams prior to distillation of the latter in order to provide a beneficial refining action during the distillation.

In the process of Figure 2, one portion of gasoline is refined by contact with caustic soda in the absence of a treating compound according to the invention, and the spent caustic soda obtained upon separation of layers is then contacted with a second portion of gasoline, to which acrylonitrile has been added. The conditions of treatment may be generally similar to those employed in the process of Figure 1. The refined gasoline obtained by treatment with spent caustic soda in the presence of acrylonitrile will be found to be highly improved in properties, whereas a treatment with spent caustic soda in the absence of acrylonitrile would be ineffective as a practical matter.

In the Figure 2 process, it is believed that the acrylonitrile probably reacts with sodium mercaptides contained in the spent caustic soda to convert those mercaptides into sodium hydroxide and non-objectionable compounds containing mercaptan residues. The latter compounds may be extracted in part from the caustic by the gasoline in the second caustic treatment; if so, they are not objectionable in the gasoline, and their removal from the caustic soda leaves the latter in good condition for contacting additional gasoline.

The spent caustic soda may contain sodium phenolates and/or sodium naphthenates, in addition to sodium mercaptides. The latter generally react more readily with acrylonitrile than do the phenolates and naphthenates, and therefore spent caustic soda which has been con-

3

tacted with acrylonitrile or other treating compound according to the invention generally has improved solvent power for sodium mercaptides, by virtue of the solutizing effect of the phenolates and naphthenates.

In the process of Figure 3, caustic soda in the absence of caustic soda.

In the process of Figure 3, gasoline is contacted with caustic soda in the absence of acrylonitrile, and the spent caustic soda is regenerated, after separation from the refined gasoline, by contact with acrylonitrile. The regeneration may be effected by adding the acrylonitrile to the gasoline at ordinary temperature without heating and agitating the caustic to obtain good contact. If desired, elevated temperatures, e. g. up to 200° F. or higher can be employed. Generally, the amount of acrylonitrile or other treating compound employed will be within the range from 0.01 to 10 parts by weight per 100 parts of 15 caustic soda, more preferably 0.1 to 5 parts per 100. The amount of treating compound may be chosen such that sodium mercaptides are preferentially reacted with the treating compound, phenolates and naphthenates, leaving largely unreacted. The regeneration may be used to contact additional material.

4

the latter used is a minor amount, preferably in the range from 0.5 to 25 parts by weight per 100 parts of petroleum material, more preferably from 1 to 10 parts per 100. The concentration of the caustic soda will generally be in the range from 5 to 25 percent, though higher or lower concentrations can be used.

The reaction involved in the invention is believed to be a double hydrolysis reaction.

The reaction involved in the treatment according to the invention is believed to be an addition across the double bond of the treating agent; thus, in the case of a mercaptan, RSH , the $RS-$ radical probably attaches to one of the ethylenic carbon atoms and the hydrogen atom to the other ethylenic carbon atom.

The invention claimed is:

1. Method for refining mineral oil which contacting mineral oil containing action conditions with
